UNITED STATES PATENT OFFICE.

THURE E. DAHL, OF NEW YORK, N. Y.

DESIGN FOR A WALL BRACKET FOR LIGHTING FIXTURES.

Application filed July 3, 1923. Serial No. 6,665. Term of patent 3½ years.

To all whom it may concern:

Be it known that I, THURE E. DAHL, a citizen of the United States, and residing at New York, in the county of New York and State of New York, have invented a new, original, and ornamental Design for a Wall Bracket for Lighting Fixtures, of which the following is a specification, reference being had to the accompanying drawing, forming part thereof.

Fig. 1 is a side view of a wall bracket for lighting fixtures, showing my new design.

Fig. 2 is a front view of the same.

I claim:

The ornamental design for a wall bracket for lighting fixtures, as shown

THURE E. DAHL.
